UNITED STATES PATENT OFFICE.

PAUL WHITING, OF EAST LASVEGAS, TERRITORY OF NEW MEXICO.

AIR-BRAKE SYSTEM.

SPECIFICATION forming part of Letters Patent No. 684,735, dated October 15, 1901.

Application filed August 28, 1900. Serial No. 28,311. (No model.)

To all whom it may concern:

Be it known that I, PAUL WHITING, a citizen of the United States, residing at East Las-
vegas, in the county of San Miguel and Ter-
ritory of New Mexico, have invented new and
useful Improvements in Air-Brake Systems,
of which the following is a specification.

My invention relates to air-brake systems;
and one object of the same is to provide re-
liable means for indicating and regulating the
brake-pressure, said means being located
within the cab of the engine and under direct
control of the engineer.

Another object of my invention is to pro-
vide a straight air-brake system which will be
simple in construction and operation and
which will permit the engineer to increase or
reduce the pressure at all times, to prevent
the necessity of clubbing the brakes, or to in-
crease or diminish the pressure to control the
speed.

These objects are attained by means of the
construction illustrated in the accompanying
drawings, in which—

25 Figure 1 is a diagrammatic view illustrating
the general plan of my system. Fig. 2
is a vertical sectional view taken centrally
through the two-way cock. Fig. 3 is an end
elevation of my engineer's valve. Fig. 4 is a
30 development of the lower half of the inner
cylinder of the engineer's valve. Fig. 5 is a
development of the lower half of the outer cyl-
inder of said valve. Fig. 5^a is a transverse
35 section of the cylinder-valve through one se-
ries of ports. Fig. 5^b is a transverse section
of the cylinder-valve through the other series
of ports. Fig. 6 is a side elevation of the
hose-coupling. Fig. 7 is a longitudinal sec-
40 tion of one member of said coupling. Fig. 8
is a vertical section of the whistle-valve. Fig.
9 is a vertical section of the reducing-valve.
Fig. 10 is a perspective view of the ferrule in
combination with a section of the sleeve. Fig.
45 10^a is a detail section of the catch.

Like characters of reference designate like
parts wherever they occur in the different
views.

Several of the devices included in this sys-
tem are not claimed specifically, but are cov-
50 ered by the following patents or applications
for patents: allowed application for patent,
filed September 12, 1900, Serial No. 29,799; al-

lowed application for patent, filed July 25,
1900, Serial No. 24,837; Patent No. 666,171,
of January 15, 1901.

55 In the drawings the numeral 1 designates
the cylinder-valve, 2 is the reducing-valve,
3 is the pressure-indicator, 4 is the whistle-
valve, 6 is the hose-coupling, and 7 is the two-
way cock.

60 The cylinder-valve consists of an inner cyl-
inder 8, inclosed within a two-part cylinder
or housing 9. The outer surface of the inner
cylinder and the inner surface of the outer
cylinder are ground to form a tight joint. 65
The inner cylinder has a stub-shaft 10, pro-
jecting through the end of the outer cylinder,
and an operating-handle 11 is secured to the
end of said stub-shaft. Stop-lugs 12 are
formed near the end of the outer cylinder to
70 engage the spring-bolt 13 of the handle 11.
There are five stop-lugs illustrated and each
lug represents a different position of the valve.
The inner cylinder is hollow and is provided
with seven ports (designated 1' to 7', inclu-
75 sive) and the outer cylinder has three ports,
(designated 8' to 10', inclusive.) These ports
are of two different sizes and are brought into
register by the handle, and the five positions
of this handle correspond to rapid exhaust,
80 slower exhaust, cut-off, small supply, and
large supply.

75 When the valve is set in the first position,
the ports 5' and 9' and 4' 8' will register and
the brake-cylinder will exhaust rapidly. 85
When set in the second position, the ports 4' 9'
and 3' 8' will register, giving a slow exhaust.
When set in the third position, all ports will
be blanked, giving a cut-off. When set in the
fourth position, the ports 7' 10' and 2' 9' will
90 register, thus giving a small supply to brake-
cylinder. When set in the fifth position, the
ports 6' 10' and 1' 9' will register, giving a
larger supply.

95 The reducing-valve 2 is connected to the
valve 1 by the pipe 18, and consists of a cy-
lindrical casing 19, with an apertured valve
20 seated in the head of said casing and com-
municating with said pipe 18. A piston 21
100 fits snugly within the casing and is provided
with a longitudinally-apertured stem 22. Se-
cured into the lower end of the aperture 23 is
a conical valve-seat 24, which fits the valve
20. The stem 22 is encircled by a spring 25,

held in place by an adjusting-nut 26. This stem is annularly grooved at 27, and passages 28 establish communication between said groove and the longitudinal aperture 23. The 5 upper portion of the casing 19 is reduced in size and surrounds the stem 22, and two small slots 29^a are formed in this casing just opposite the position of the groove 27 when the piston is raised against the stress of the spring 10 25. A collar 28^a surrounds the casing 19, and seated on said collar and fitted snugly to the casing is a ferrule 29, triangularly apertured at 30. A threaded sleeve 31 is screwed onto the upper end of the casing and extends down 15 to near the top of the ferrule. Two catches 32 are seated in the lower rim of said sleeve and engage a series of teeth 32^a, formed in the top of said ferrule. These teeth are rounded, so that the catches will ride over them in 20 either direction, and are provided to make the movement of the ferrule more positive. The top of the sleeve 31 is capped by a nut 33, which is high enough to obviate the danger of being struck by the stem when the 25 valve is suddenly unseated. The tension of the spring 25 is adjusted to a previously-determined pressure. When the pressure in the pipe exceeds the tension of the spring, the valve will be unseated and air will escape by way of the groove 27, passages 28, triangular aperture 30, and slots 29^a. The 30 rate of egress of the air may be regulated by the ferrule 29.

The whistle-valve 4 consists of an outer 35 casing 34, a piston 35, having a hollow stem 36, surrounded by a spring 37, a valve-seat 38, and a head 39, provided with passages 40. A whistle 41 is secured at the top of the casing 34, and a nut 42 regulates the tension of 40 the spring 37. In operation the spring 37 is adjusted to be of slightly less tension than the spring in the reducing-valve to give an alarm before the action of the reducing-valve.

The pressure-gage 3 may be of the usual construction and may be connected to pipe 14 between the cylinder-valve 1 and the reducing-valve 2.

The hose-coupling 6 consists of two interlocking members 6^a 6^b, each member having a 50 spring-seated valve 6^c therein. This valve is provided with an enlarged head 6^d, seated by the stress of spring 6^e on the valve-seat 6^f, as shown in Fig. 7. The valve-stem 6^g extends upward from the head 6^d into a cap-nut 6^h 55 and downward from said head through the wall of the coupling member 6^b, and near its end it is provided with a packing-ring 6ⁱ. A rubber gasket 6^j is seated in a socket in the coupling. A flange 6^k extends outward under the valve-stem 6^g and is provided with ridges 6^l and a vertical wall 6^m. Between the ridges 6^l and the wall 6^m a curved guide-way 6ⁿ is formed. A wedge-shaped tongue 6°, transversely curved and extending across 65 the member 6^b, is adapted to fit under the end of the valve-stem 6^g to hold the valve open when the two sections are coupled together.

It will be understood that the members 6^a and 6^b are identical in structure and that when coupled together the tongues 6° hold the valves open against the stress of springs 6^e and that the two members of the coupling are disposed at an angle to each other. When the cars separate and the coupling is pulled out straight, the members 6^a 6^b uncouple and 70 close their valve automatically by means of the springs 6^e. When the members are coupled, the ridges 6^l interlock and hold the members together, and communication is established through said members by way of 75 passage 6^p and through the aperture in the gasket 6^j. When the members are coupled, the valves are opened and communication is 80 established through the coupling. Should the cars be separated, the coupling would 85 straighten out and uncouple automatically and the valves would be forced to their seats by the springs in each member of the coupling.

The two-way cock 7 consists of a T-coupling having a ball-valve seated in a recess at 90 the junction of the three stems of the T, the ball being provided with a central bore 15. A handle 17 is connected to the valve for turning it into different positions. This cock is located at the junction of a pipe leading 95 from the triple-valve exhaust and the supply-pipe. This cock is set to cut off the exhaust, and thus prevents the brakes from being released when the engineer's valve of the Westinghouse system is turned to releasing position. 100

My system may be used in combination with the usual Westinghouse automatic brake system, as shown, *a* being the main reservoir; *b*, the engineer's valve; *c*, the triple valve; 105 *d*, the auxiliary reservoir; *t*, the brake-cylinder; *f*, the equalizing-reservoir, and *g* the pressure-gage. The brake-cylinder *t* and auxiliary *d* are connected to the triple *c* by pipes *h* and *i*, respectively, in the usual manner. 110 The triple *c* is also connected to a first train-line *j* by a pipe *k*. The engineer's valve *b* is at the termination of the train-line *j*, which is connected to the main reservoir *a* by a pipe *l*. 115 It is also connected to the gage *g* and equalizing-reservoir *f* by pipes *m* and *n*, respectively. 120

The mechanism peculiar to my system is all connected to a second or auxiliary train-line *A*, which terminates at and is connected to 125 the cylinder-valve 1. The gage 3, safety-valve 2, and whistle 4 are connected to the line *A* by branch pipes joined thereto at points above the main reservoir *a*, which is also connected to the line *A* by a pipe *B*, normally closed by a valve *D*. Branches *C* on each car (only one is shown) connect the 130 brake-cylinder *t* with the line *A*. The line *A* is connected to the cylinder-valve 1 by a coupling which communicates with the port 9'. 135 A pipe *E* establishes communication between the two train-lines and is joined to the pipe *l* at a point just below the engineer's valve and to the cylinder-valve 1 by a connection 140

which communicates with the port 10'. The port 8' opens into the air.

Given the above connections, the path of the air when the handle 11 on the cylinder valves is set in its different positions can now be traced. First position: from brake-cylinder *t* to line A, through ports 9' and 5' and ports 4' and 8', to open air; slow exhaust. Second position: from brake-cylinder *t* to line A, through ports 9' and 4' and ports 3' and 8', to open air; rapid exhaust. Third position: all ports blanked; cut off. Fourth position: from main reservoir *a* to pipe E, through ports 10' and 7' and ports 2' and 9', to line A and through pipe C to brake-cylinder *t*; small supply. Fifth position: main reservoir *a*, pipe E, ports 10' and 6', ports 1' and 9', line A, and pipe C, to brake-cylinder *t*; large supply.

The operation of a system thus equipped is as follows: Under normal conditions the air-pressure in the train-line and the auxiliary reservoir will be equal, the handle 11 of valve 1 being in position to exhaust the brake-cylinder. Consequently if any triple valve is defective in the train the brakes will be nevertheless released. The handle 11 may be placed in the second position, corresponding to a slower exhaust. This will usually be the case when the train is running fast. When brakes are to be applied, the handle 11 is thrown over to the central stop or lug, blanking all the ports. The brakes may now be set by the Westinghouse system by making a slight reduction of pressure in the train-line by use of the valve *b*. The handle 11 can now be thrown over to the third position and the brakes held while the engineer's valve *b* is set at released position and the auxiliary reservoir pumped up. If the brakes are now set too hard, the handle 11 may be turned over to a partial release in second position and back to the third position and a portion of the air thus released from the brake-cylinder. The decrease in pressure will be indicated on the gage 3. It will be noted that the brakes will remain set after the valve *b* has been set at release position if the handle 11 is set in the third position, blanking all ports, because the cock 7 is set to cut off the exhaust of the brake-cylinder. The brakes can only be released by setting the handle 11 at either the first or second position. If it is desired, as in cases of emergency or when the pressure in the auxiliary reservoirs is very low or when one of the triple valves is defective, straight air may be used by setting the handle 11 at either the fourth or fifth position. As hereinbefore stated, the fourth position will apply the brakes gradually and the fifth position more rapidly, owing to the larger size of the ports. The reducing-valve 2 will be set to blow off at a certain predetermined pressure and will thereby prevent the air-pressure from exceeding a certain amount. This will prevent the use of excessive pressure, causing the flattening of wheels. The whistle-valve 4 is set to respond

to a pressure slightly less than that of the reducing-valve and the engineer is warned of the rise of pressure by the sound of the whistle. Should the train part, the coupling 6 would straighten out and uncouple and the valves in the coupling members would be forced by their springs to their seats and prevent the loss of air. Should the train part 75 when the brakes are set, in case the rear end of the train is not brought to an immediate stop by the action of the brakes the engineer may quickly release the brakes on the forward end by the use of handle 11, and thus keep it 80 well ahead of the rear end until danger of collision is past. When the rear end has come to a stop, the front end may be backed up and coupled and the brakes immediately released by the use of handle 11 without waiting to 85 pump off the brakes or bleed the cars.

From the foregoing description the following advantages may be gleaned, and briefly summarized they are as follows: It is impossible for brakes to stick with the handle 11 set 90 in releasing position. The auxiliary reservoirs may be refilled while the brakes remain set. The pressure in the brake-cylinders can be reduced without releasing any part of the air from the main line or auxiliary reservoir. 95 The danger of flattening the wheels can be greatly reduced, if not entirely obviated. If the train parts, all brakes can be released on the forward section until the rear section stops. In coupling up after the break all 100 brakes may be released without waiting to pump them off. Waste of air may be reduced to the minimum by setting the cylinder-valve at the released position as soon as the brakes have been applied. The engineer can see 105 brake-cylinder pressure at all times. Brakes can always be applied, even when the triple valves are defective.

Having thus fully described my invention, what I claim is—

1. In an air-brake system, the combination, substantially as described, of a first train-line, a main reservoir, a triple valve, an auxiliary reservoir, and a brake-cylinder, all four connected to said first train-line, a second or auxiliary train-line connected to said brake-cylinder, a cylinder-valve connected to both said first and second train-lines, a pipe connecting the exhaust of said triple to said second train-line, and a two-way cock located at the junction of said pipe and said second train-line.

2. In an air-brake system, the combination, substantially as described, of a first train-line, a triple valve, a main reservoir, an auxiliary reservoir, a brake-cylinder, and an engineer's 125 valve, all five connected to communicate with said first train-line, a second train-line connected to said brake-cylinder, a cylinder-valve connected to both said first and second pipe-lines, a pipe connecting the exhaust of 130 said triple to said second train-line, and a valve located at the junction of said pipe and said second train-line.

3. In an air-brake system, the combination,

of a first train-line, a main reservoir, a triple valve, an auxiliary reservoir, and a brake-cylinder, all four connected to said first train-line, a second train-line connected to said 5 brake-cylinder, a reducing-valve, a whistle, a gage all three located in the cab and connected to said second train-line, an engineer's valve located in the cab and connected to said first train-line, and a cylinder-valve located

in the cab and connected to both said first and 10 second train-lines.

In testimony whereof I have hereunto set my hand in presence of two subscribing witnesses.

PAUL WHITING.
